UNITED STATES PATENT OFFICE.

WILLIAM E. HOLDEN, OF CRESCENT CITY, CALIFORNIA.

CONTAINER.

Application filed August 29, 1921. Serial No. 496,704.

To all whom it may concern:

Be it known that I, WILLIAM E. HOLDEN, a subject of Great Britain, residing at Crescent City, Del Norte County, and State of California, have invented a new and useful Improvement in a Container, of which the following is a specification.

My invention relates to containers for plastic substances wherein a pliable envelope 10 formed from a non-metallic material is mounted within a casing and arranged to be twisted to expel the contents through a spout.

The primary object of my invention is to 15 provide an improved container for plastic substances such as tooth paste, cold cream and the like.

Another object of my invention is to provide a container in which a plastic substance 20 may be retained and from which it may be expelled without contact with metal.

A further object of my invention is to provide improved means for dispensing a plastic substance from a container.

A still further object is to provide an improved device of the character described that presents a pleasing appearance and which may be manufactured at a low cost.

A still further object is to provide a container which may be packed for shipping, or carried among the personal effects of a user without danger of breakage with the resultant loss of contents and damage to surrounding objects.

I accomplish these and other objects by means of the device disclosed in the drawings forming a part of the present specification wherein like characters of reference are used to designate similar parts throughout said specification and drawings and in which,

Fig. 1 is a vertical section of my improved container disclosing one manner by which to compensate for the shortening of the envelope.

Fig. 2 is a broken side elevation of Fig. 1 showing the envelope partially twisted to expel a portion of the contents.

Fig. 3 is a broken side elevation showing another manner of compensating for the shortening of the envelope.

Fig. 4 is a side elevation partially broken away and shown in vertical section to disclose a modified form of casing arranged to permit shortening of the envelope.

Figs. 5, 6, and 7, are broken vertical sec-

tions showing further methods by which it is possible to compensate for the shortening of the envelope when twisted.

Referring to the drawings the numeral 1 is used to designate in general a casing provided with a rotatable cap 2 having a spout 3 formed thereon, and a bottom plate 4. An envelope 6 is secured between the cap 2 and the plate 4 and arranged to receive a quantity of a plastic substance 7 in such a manner that when either the cap or casing is rotated with respect to the other, the envelope will be twisted to expel the contents therefrom through the spout 3.

The casing 1 may be made of any desired shape or ornamental design, but for convenience in illustration I have shown it as a cylindrical member having annular flanges 8 outwardly turned upon the ends. The bottom plate 4 is held against the lower flange 8 by crimping a base piece 9 to enclose the flange and the edge of the plate. The cap 2 is shaped upon the edge thereof to form a pair of annular channels 11 and 12, the lower channel 12 being turned over the upper flange 8 to form a rotatable connection therewith.

The cap 2 is provided with a lining 13 shaped to fit the inner side of the cap, the outer edge of the lining 13 being introduced into the channel 11 and the inner edge being brought outwardly through the spout and secured by a threaded collar 14 crimped upon the outer side of the spout 3. A closing cap 16 is threaded to screw onto the collar 14 to normally close the spout.

The edge of the envelope 6 at the large end of the cone is introduced into the channel 11 together with the lining 13 and the adjacent portions of the cap crimped together to firmly secure both the lining and the top of the envelope. In this manner the casing and cap is completely lined in such a manner that any substance introduced into the containing envelope 6 will be completely protected from contact with metal or other material from which the casing members are made.

The small end of the envelope 6 is secured to the bottom in any convenient manner, as by passing the extreme tip of the envelope through an aperture 17 and firmly clamped against the plate 4 by means of a disc 18, as shown in Fig. 1, or by securing the tip directly upon the top of the plate in any suitable manner.

By securing the envelope between the rotatable cap 2 and the bottom plate 6, a rotation of the cap with respect to the casing will operate to twist the envelope, and as the stress will be imparted to the apex of the cone where the resistance is the least, the contents of the envelope will be forced upwardly and out through the spout 3 when the closing cap 16 is removed. As is readily seen, the continued relative rotation of the cap and the casing in the same direction will tighten portion at the lower end of the envelope and at each rotation a greater portion of the lower end of the envelope will be closed up and the contents eventually all forced upwardly and out of the envelope.

By twisting the envelope 6 in the manner above described, the envelope would normally become so shortened as to prevent total closure. To provide the additional length of material necessary to compensate for the shortening of the envelope it is essential that means be provided for lengthening the envelope in proportion to the amount of material taken up by the twist. In the drawings I have illustrated several methods by which this may be accomplished. In Fig. 1, I have shown the envelope 6 as formed with a plurality of pleats 19 which are normally held in folded position by starch or other stiffening material. As the envelope is twisted the pleats are drawn into extended position as shown in Fig. 2 of the drawings in this manner providing an additional amount of material sufficient to permit the envelope to be twisted to the top thereby entirely expelling the contents.

In Fig. 3 I have illustrated the envelope 6 as provided with a plurality of folds 21 normally held between adjacent coils of a spring 22, the pressure of the spring operating to hold the excess material in reserve until the twisting stress becomes sufficient to free the folds successively from the spring.

In Fig. 4 I have illustrated a modified form of the device in which the casing 1 is formed from telescoping members 1^a and 1^b. A rotation of either member relative to the other will operate to twist the envelope 6 and the inner member 1^b is free to advance into the outer member 1^a to compensate for the shortening of the envelope due to the twisting, as shown in dotted lines.

Fig. 5 illustrates another manner of providing additional material for the envelope, in this form, the tip of the envelope being drawn through a small aperture 23 in a resilient disc 24 of rubber or other suitable material secured upon the bottom plate 6 to cover a larger aperture 26 therein. The excess material is held in reserve below the bottom plate, the frictional resistance of the disc 24 being adapted to permit the end of the envelope to be drawn into the casing as

needed to compensate for the shortening of the envelope. A link 27 is secured on the end of the envelope to prevent the end from being drawn into the casing through the aperture 23.

Fig. 6 shows a spring 28 secured upon the top of the plate 6 to which is secured the tip of the envelope 6. The spring is made of a size adapted to resist torsion and to permit longitudinal extension sufficient to compensate for the total shortening of the envelope.

Fig. 7 discloses a still further method of compensating for length, by slidably mounting the bottom plate 4 within the lower portion of the casing 1, the edges of the plate 4 being notched to engage ribs 29 formed upon the inner side of the casing. The disc is made to fit tightly in the casing so as to be drawn upwardly only in accordance with the shortening of the envelope as shown in dotted lines. The ribs 29 prevent rotative movement of the plate 4 thereby causing the envelope to be twisted as hereabove described.

From the above description it is readily seen that my improved container is subject to wide variation in structure without departing from the spirit of my invention. The materials of construction may be varied to suit the requirements of any specific product, and the design made to afford distinctiveness to the original product and to serve for ornamental purposes or as a toy after the contents have been removed.

My improved container is particularly designed to prevent contact with metal or other materials by which the contents of the container may in any manner become contaminated or rendered unsanitary. In collapsible metal tubes of the character commonly employed as containers for plastic substances of the character above mentioned, there is always the likelihood of certain chemical reactions between the metal of the container and the chemical composition stored therein, such reactions often contaminating the contents by the formation of reaction products of a detrimental character. My improved device, being entirely lined with a material which may be selected to meet the requirements of any particular product, effectually prevents such contamination. The device may be manufactured at a low cost and the container will retain its original pleasing appearance even after the contents have been expelled.

Having thus described my invention what I claim as new and desire to secure by Letters Patent is:

1. A container for plastic substances comprising a casing; an envelope secured at both ends within said casing to receive the plastic substance; means for twisting said envelope within the casing to expel the contents there-

from; and means for compensating for the shortening of the envelope due to twisting.

2. A container for plastic substances comprising a casing; a conical envelope secured at both ends within said casing to receive the plastic substance; means for twisting said envelope within the casing to expel the contents therefrom; and means for compensating for the shortening of the envelope due to 10 twisting.

3. A container for plastic substances comprising a casing; a conical envelope formed from pliable material secured at both ends within the casing; a spout formed upon the 15 casing adjacent the large end of the envelope; means engaging the small end of the envelope for twisting the envelope to expel the contents therefrom through the spout; and means for compensating for the shortening 20 of the envelope due to twisting.

4. A container for plastic substances comprising a casing; one end of said casing being adapted for rotative movement relative to the other end; a conical envelope formed 25 from suitable pliable material mounted within the casing, the ends of said envelope being secured upon opposite ends of the casing whereby rotation of one end of the casing relative to the other end thereof will 30 operate to twist said envelope and expel the contents therefrom; and means for compensating for the shortening of the envelope due to twisting.

5. A container for plastic substances comprising a casing; one end of said casing being adapted for rotative movement relative to the other end; a dispensing spout formed upon one end of the casing; a conical envelope mounted within the casing, the large 35 end of said conical envelope being secure ad-

acent the spout, and the small end being secured at the opposite end of the casing whereby rotative movement of either end of the casing relative to the other end thereof will operate to twist the envelope and expel 45 the contents thereof through the spout.

6. A container for plastic substances comprising a casing, one end of said casing being adapted for rotative movement relative to the other end; a dispensing spout formed upon 50 one end of the casing; a conical envelope mounted within the casing, the large end of said conical envelope being secured adjacent the spout, and the small end being secured at the opposite end of the casing whereby rotative movement of either end of the casing relative to the other end thereof will operate to twist the envelope and expel the contents 55 thereof through the spout; and means for compensating for the shortening of the envelope due to twisting.

7. A container comprising a casing; a rotatable cap mounted upon one end of said casing; a dispensing spout formed upon said cap; a lining secured within the cap and 60 spout; a conical envelope mounted within the casing, the large end of said envelope being secured upon said cap by crimping the edge of said cap upon the envelope; means for securing the small end of the conical envelope to the other end of the casing whereby rotation of the cap relative to the casing 65 will operate to twist the envelope and expel the contents of the envelope through the 70 spout; and means for compensating for the 75 shortening of the envelope due to twisting.

In witness whereof I hereunto set my signature.

WILLIAM E. HOLDEN.
